FLAP-APPLYING MACHINE

Herbert J. Willmott, Beverly, Mass., assignor to
 United Shoe Machinery Corporation, Borough
 of Flemington, N. J., a corporation of New
 Jersey

Application February 28, 1939, Serial No. 259,003

11 Claims. (Cl. 12—125)

This invention relates to machines for use in the manufacture of shoes and is illustrated as embodied in an improved machine for quickly and effectively applying to Louis heels and shank portions of the soles of shoes covering flaps, which have their inner faces coated with adhesive and which have been previously laid up by hand against the breasts of said heels, and for holding the flaps clamped to the heels until the flap-securing adhesive dries.

In accordance with a feature of this invention the illustrated flap-applying machine comprises a support having stationary and movable members, a resilient pad mounted upon the support and constructed and arranged to be interposed between the shank portion of a shoe and the breast of an attached Louis heel of the shoe against which breast a covering flap has been laid, means for forcing the covered breast of the heel against the pad, and means for operating the movable member of the pad support to expand the pad and to force the same with considerable pressure against the upper end of the covered breast of the heel and the shank portion of the sole of the shoe. The shoe against the breast of the heel of which the flap has been previously laid by hand, is positioned upon the pad which is wedge shaped and is preferably made of rubber. The operator then depresses a treadle causing 0 through mechanism comprising a toggle, a pair of clamps to force the covered breast of the heel against one wedge-face of the pad and causing the movable member of the pad support to swing the other wedge face of the pad with considerable force against the shank portion of the shoe. In clamping the shoe in the machine the toggle is straightened and locked so as to hold the pad in clamped relation to the shoe until the flap-securing adhesive dries. The toggle is then broken and the clamps are returned to their initial positions, the shoe in the meanwhile being removed from the machine. By providing a pad support having a movable member for expanding the pad, the machine is adapted to accommodate 15 a wide range of sizes and styles of shoes and heels without having to change the pad.

It has been found that when the work-engaging portions of flap-applying pads are made entirely of soft readily yieldable rubber there is a 10 tendency when considerable pressure is applied against the flap-covered breast of the heel of the shoe for any surface imperfections in the breast of the wood heel block to appear through the covered heel breast. Such a condition is undesirable, especially in the upright portion of the

heel breast which is exposed to view when the shoe is worn. In order to insure against surface imperfections in the upright relatively flat portion of the breast of the wood heel block showing through the applied flap, and in accordance with another feature of the present invention, the wedge-face portion of the pad which applies the flap to the upright portion of the heel block is made of relatively hard but slightly yieldable rubber, the other wedge-face portion of the pad being made of soft readily yieldable rubber so that it will conform readily to the overhanging portion of the breast of the heel and the shank portion of the sole of the shoe. The relatively hard wedge-face portion of the pad is sufficiently 10 yieldable to conform to the upright portion of the heel breast but is rigid enough to insure against small areas of the flap being pressed into small 15 cavities or other surface imperfections in the breast of the wood-heel block and therefore 20 showing through the covered breast of the heel.

The various features of the invention will be understood and appreciated from the following detailed description read in connection with the accompanying drawings, in which

In the drawings,

Fig. 1 is a perspective view, partly broken away, of the illustrated machine;

Fig. 2 is a side elevation, partly in section and partly broken away, of the machine;

Fig. 3 is an exploded view showing in perspective the rubber pad for applying the covering flap to the Louis heel and the shank portion of the sole of the shoe and the support for the pad;

Fig. 4 is a side elevation of the flap-applying pad and support illustrated in Fig. 2 when the machine is idle;

Fig. 5 is a section on line V—V of Fig. 2; and

Fig. 6 is a perspective view of the heel end of an inverted shoe the covering flap of which has 40 been laid by the above machine.

The illustrated machine is described with reference to applying a covering flap 20 (Fig. 6) to the breast of an attached heel 24 (Figs. 2 and 6) of a shoe 26 and to the shank portion 28 (Fig. 6) 45 of the sole of the shoe, and comprises a support 30 for a wedge-shaped rubber pad 32, and heel and last engaging clamps 34, 36, respectively, for forcing the shoe against the pad, the pad support 30 comprising an arm 38 which, during the 50 clamping movement of the clamps 34, 36 is swung in a clockwise direction, as viewed in Fig. 2, to expand the pad.

Before presenting the shoe, which is usually mounted upon a last 37 (Fig. 2) to the machine 55

the operator positions and lays the flap 20 (Fig. 6), the inner face of which has been previously coated with cement or other suitable adhesive, against the breast 22 of the heel and the shank portion 28 of the sole of the shoe. The shoe is then placed in the machine with the relatively flat upright portion 40 of the covered breast of its attached heel in engagement with the flat wedge face 42 (Figs. 3 and 4) of the pad 32 and with the sharply curved or vertex portion 44 of the pad in engagement with the forwardly projecting or overhanging portion of the covered breast of the heel. The operator then depresses a treadle 46 (Fig. 1) causing, through mechanism which will be described later, the respective clamps 34, 36 to force the attached heel of the shoe against the pad 32, and also causing the expander arm 38 to swing the concave wedge face 48 of the pad toward and against the shank portion of the sole of the shoe. In order to hold the flap 20 securely in place against the breast of the heel and the shank portion of the sole until the flap-securing cement dries, the treadle-operated mechanism comprises a toggle 50 which, when the treadle 46 is depressed, is straightened and temporarily locked, as shown in Fig. 2.

The support 30 for the pad 32 comprises a table 52 (Figs. 2, 3 and 4) and the pad expander arm 38 which is pivoted upon a fulcrum pin 54 carried by the forward end of the table. The table 52 has a flat upper face 56 (Figs. 3 and 4) and is secured to the main frame of the machine by screws 58 (Figs. 2 and 4). When the machine is idle the expander arm 38 is in its raised position adjacent to the table 52, as illustrated in Fig. 4. The pad 32 has in its rear end a deep groove 60 (Fig. 3) shaped and arranged to enable the operator to slide the pad over the forward ends of the expander arm 38 and the table 52 when the machine is in its idle position shown in Fig. 4, the pad being positioned widthwise upon the support by side plates 62 which are secured by screws 64 to the opposite sides of the forward end of the expander arm 38.

The heel clamp 34 comprises a concave rubber roll 64 (Figs. 1 and 2) rotatably mounted upon studs 66 threaded into the lower end of a carrier 67 which is pivoted upon a fulcrum pin 68 secured to a lever 70. The lever 70 is pivoted upon a fulcrum pin 72 supported in a bearing 74 of the machine frame and has secured to it by screws 76 (Fig. 2) a segment plate 78 (Figs. 1 and 2) having an arcuate slot 80 which is centered about the axis of the fulcrum pin 68. Housed in a bore of the carrier 67 is a screw 82 (Fig. 5) the shank portion of which passes through the arcuate slot 80 of the segment plate 78 and is threaded into a stud 84 which fits in another bore of the carrier. When the stud 84 is turned in a clockwise direction as viewed in Figs. 1 and 2 the opposing shoulders of the screw 82 and the stud 84 are forced against the opposite sides of the segment plate 78 to secure the same to the carrier 67. The carrier 67 may be secured in different angular positions upon the fulcrum pin 68 in accordance with the shape of the heel of the shoe being operated upon, after releasing the stud 84. When the proper adjustment has been effected the carrier 67 is again clamped against the segment plate 78 secured to the lever 70 by tightening the stud 84.

Pivoted upon studs 86 threaded into the lever 70 is a trunnion 88 having at its central portion a bore through which passes a rod 90 to the upper

end of which a hand hold 92 is secured. Surrounding the rod 90 and interposed between the trunnion 88 and a nut 94 threaded onto the rod is a spring 96 which, when the machine is idle, forces a flange 98 of the rod against the lower portion of the trunnion 88.

Threaded into a bore of the rod 90 is another rod 100 the lower end of which is threaded into a trunnion 102 pivoted at its opposite ends in the rear end of a bell-crank lever 104 mounted upon a fulcrum pin 106 supported by the machine frame. A check nut 108 is threaded onto the lower end of the rod 100 and is normally forced against the trunnion 102. The front arms of the bell-crank lever 104 are pivotally connected by a fulcrum pin 110 to the toggle 50 which comprises front and rear arms pivotally connected by a toggle pin 112, the central portion of which fits in an elongated slot 114 of a toggle-operating link 116. The rear arms of the toggle 50 are secured to a pin 117 which is mounted in a bearing of the machine frame. When the treadle 46 is depressed the link 116 is raised to the position shown in dotted lines (Fig. 2) until the forward arms of the toggle 50 engage stops 118 on the machine frame thereby closing and locking the toggle 50 and operating the clamps 34, 36 and the pad-expanding arm 38.

The last-engaging clamp 36 comprises a bifurcated lever 120 the lower ends of which are pivoted upon the fulcrum pin 106, and a block 122 which is mounted upon a stud 124 secured to the upper end of the lever. The upper end of the block 122 is covered by a leather pad 125 which is secured to the block by a nut and bolt connection 126 (Fig. 2). In order initially to adjust the block 122 into different angular positions upon the lever 120 in accordance with the size and shape of the last 37 upon which the shoe is mounted, the block 122 is provided with an arcuate slot 130 which is centered about the axis of the stud 124 and through which passes a screw 132 threaded into the lever 120. The head of the screw 132 is forced against the block 122 to clamp the block against movement with relation to the lever 120.

The lever 120 has pivotally secured to it a rod 134 extending downward through a bore in a sleeve 136 which is threaded into the fulcrum pin 110. Threaded onto the lower end of the sleeve 136 and clamped against the under side of the fulcrum pin 110 is a nut 140, and encircling the sleeve and located between the fulcrum pin 110 and the head of the sleeve 136 is a coil spring 142. Threaded onto the upper end of the rod 134 is a hand nut 144 which is normally forced against the head of the sleeve through the provision of a spring 146 mounted upon the fulcrum pin 106 and having its opposite ends in engagement with the studs 148, 150 (Fig. 2) carried by the bell-crank lever 104 and the lever 120 respectively. The angular position of the lever 120 upon the fulcrum pin 106 can be initially varied by turning the hand nut 144. When the toggle 50 is broken the bell-crank lever 104 moves in a counterclockwise direction as viewed in Figs. 1 and 2 causing the sleeve 136 to be lowered and the lever 120 to be swung in a counterclockwise direction.

The expander arm 38 is swung in a clockwise direction as viewed in Fig. 2 about the fulcrum pin 54 to force the concave wedge face 48 of the pad 32 against the projecting portion of the covered breast of the heel as well as against the shank portion of the sole of the shoe, through

the following mechanism. Threaded onto the rod 100 is a cam 152 which may be secured in different positions on the rod by a screw 154 (Figs. 2 and 4) and a nut 156. The expander arm 38 is constantly urged downward by a pair of springs 158 the upper ends of which embrace studs 160 carried by the expander arm and the lower ends of which embrace studs 162 extending from a collar 164 which is adjustably secured to the lower portion of the rod 100 by a screw 166 (Fig. 2) and a nut 168. In order to insure that the operative parts of the machine shall return to their initial positions shown in Fig. 1 after the toggle 50 has been broken there is provided a spring 170 the upper and lower ends of which embrace studs 172, 174 (Fig. 2) secured to the main frame and the trunnion 102 respectively.

The treadle 46 is pivoted at its rear end upon a fulcrum pin 176 (Fig. 1) and is operatively connected through a rod 178 and a lever 180 to the lower end of the toggle-operating link 116. The treadle 46 is normally moved to its raised position shown in Fig. 1 by a spring 182, upward movement of the treadle being limited by the engagement of the toggle-operating link 116 with an adjustable stop 184 threaded into the main frame. When the machine is idle (Fig. 1) the toggle pin 112 is in engagement with the lower end of the slot 114 formed in the toggle-operating link 116. Upon depression of the treadle 46 the link 116 is raised to the position shown in dotted lines (Fig. 2) to move the toggle 50 to its locked position illustrated in Fig. 2 thereby clamping the work in the machine as above described. A plurality of the above-described machines are preferably arranged side by side so that the operator can clamp shoes in rotation in the respective machines while the flap-securing cement dries.

As soon as the operator has clamped the shoe in the machine he releases his foot from the treadle 46 which is then raised by the spring 182, until the toggle-operating link 116 engages the stop 184, the link being provided with the elongated slot 114 so that the treadle can be returned to its starting position without breaking the toggle.

In order to break the toggle 50 preparatory to removing the shoe from the machine the operator swings forward a hand lever 186 which is secured to the pin 117 to which the rear arms of the toggle are secured. Downward movement of the toggle pin 112 is limited by engagement with the lower end of the slot 114 formed in the link 116. As the toggle 50 is opened the clamps 34, 36 operated by the above-described mechanism swing away from the shoe about the respective fulcrum pins 72 and 106, and the pad-expanding arm 38 is forced upward to its inoperative position shown in Fig. 4 by the cam 152 carried by the rod 100.

The idle positions of the clamps 34, 36 may be varied in accordance with the size and shape of the shoe being operated upon, adjustment of the heel clamp 34 being effected by turning the rod 90 through the use of the hand knob 92, with relation to the rod 100, and adjustment of the heel-engaging clamp 36 being effected by turning the hand nut 144 upon the rod 134. It will be noted that pressure of the clamps 34, 36 against the work is applied through springs 96 and 142, respectively, and that pressure of the pad-expanding arm against the pad is applied through springs 158. With such an arrange-

ment the clamps 34, 36 and the pad-expander arm 38 will not exert excessive pressures against the work.

As above stated, it is desirable that the major portion of the pad 32 shall be made of soft, readily yieldable rubber in order that the pad may be conformed to the overhanging portion of the breast of the Louis heel and the shank portion of the sole of the shoe. In order, however, to insure that the pad 32 shall not press the flap 10 into small cavities or surface imperfections which may be formed in the relatively flat upright portion of the breast of the wood heel block, the wedge-face portion 188 (Fig. 3) of the pad 32 is made of relatively hard but slightly yieldable rubber, the remaining portion of the pad being made of soft, readily yieldable rubber.

Having described the invention, what I claim as new and desire to secure by Letters Patent of the United States is:

1. A flap-applying machine having, in combination, a support comprising stationary and movable members, a resilient pad mounted upon the support and constructed and arranged to be interposed between the shank portion of a shoe and the breast of an attached Louis heel of the shoe upon which breast a covering flap has been laid, means for forcing the covered breast of the heel against the pad, and means for operating said movable member of the support to expand the pad and thereby to force the same with considerable pressure against the upper end of the covered breast of the heel and the shank portion of the sole of the shoe.

2. In a machine for applying by the use of an adhesive a covering flap to a Louis heel and the shank portion of a sole of a shoe, a support comprising stationary and movable members, a resilient pad mounted upon the support and constructed and arranged to be interposed between the shank portion of the sole of the shoe and the breast of the heel against which the covering flap has been laid, clamps for forcing with yielding pressure the breast of the covered heel against a portion of the pad, and means operative simultaneously with the clamps for moving said movable member of the pad support with yielding pressure toward the shank portion of the sole of the shoe thereby forcing another portion of the pad against the upper end of the breast of the heel and against the shank portion of the sole of the shoe.

3. In a machine for applying by the use of an adhesive a covering flap to a Louis heel and the shank portion of a sole of a shoe, a support comprising stationary and movable members pivoted together, a wedge-shaped rubber pad mounted upon the support and constructed and arranged to be interposed between the shank portion of the sole of the shoe and the breast of the heel against which the covering flap has been laid, clamps for forcing the covered breast of the heel against one of the wedge faces and the vertex of the pad, and means for swinging the movable member of the pad support to expand the pad thereby forcing the other wedge face of the pad against the shank portion of the sole of the shoe.

4. In a machine for applying by the use of an adhesive a covering flap to a Louis heel and the shank portion of a sole of a shoe, a wedge-shaped rubber pad having a groove, a pad support comprising a fixed table and an expander arm pivoted to one end of the table, said one end of the table and an adjacent portion of the

- expander arm being constructed and arranged to fit in said groove formed in the pad, means for forcing the upright portion of the breast of the heel against which breast the covering flap has been laid against the one wedge face of the pad, and means operative in timed relation with said means for swinging the expander arm away from the table to force the other wedge face of the pad against the shank portion of the sole of the shoe.
10. 5. In a machine for applying by the use of an adhesive a covering flap to a Louis heel and the shank portion of a sole of a shoe, a wedge-shaped rubber pad having a groove in its rear face and having flat and concave wedge faces respectively, a pad support comprising a fixed table and an expander arm pivoted to one end of the table, said one end of the table and an adjacent portion of the expander arm being constructed and arranged to fit in said groove formed in the pad, means for forcing the upright portion of the breast of the heel against which breast the covering flap has been laid against the flat wedge face of the pad, means operative in timed relation with said means for swinging the expander arm away from the table to force the other wedge face of the pad against the shank portion of the sole of the shoe, and means for locking the shoe in clamped relation to the pad while the adhesive used to secure the flap to the heel dries.
15. 6. In a machine for applying by the use of an adhesive a covering flap to a Louis heel and the shank portion of a sole of a shoe, a support comprising stationary and movable members, a resilient pad mounted upon the support and constructed and arranged to be interposed between the shank portion of the sole of the shoe and the breast of the heel against which the covering flap has been laid, clamps for forcing the covered breast of the heel with yielding pressure against a portion of the pad, spring-operated means for moving said movable member of the pad support toward the shank portion of the sole of the shoe to expand the pad thereby forcing another portion of the pad against the upper end of the breast of the heel and against the shank portion of the sole of the shoe, and a cam for positively moving said movable member of the pad support back to its initial position.
20. 7. In a machine for applying by the use of an adhesive a covering flap to a Louis heel and the shank portion of a sole of a shoe, a support comprising a fixed table and an arm mounted for swinging movement with relation to the table, a resilient wedge-shaped pad mounted upon the support and constructed and arranged to be interposed between the shank portion of the sole of the shoe and the breast of the heel against which the covering flap has been laid, a pair of clamps, means for operating the clamps to force the breast of the covered heel with yielding pressure against one wedge face of the pad, means for swinging the arm of the pad support to force the other wedge face of the pad against the upper end of the breast of the heel and against the shank portion of the sole of the shoe, said means for operating the clamps and the arm comprising a toggle, means for locking the toggle to retain the pad in clamped relation to the shoe until the flap-securing adhesive dries, and means for breaking the toggle to enable the clamps and the arm to return to their initial positions.
25. 8. In a machine for applying by the use of an adhesive a covering flap to a Louis heel and the shank portion of a sole of a shoe, a wedge-shaped pad, a support for the pad, one of the wedge-face portions of the pad being made of relatively hard but slightly yieldable rubber and the other wedge-face portion of the pad being made of relatively soft yieldable rubber, means constructed and arranged to cause the upright portion of the covered breast of the heel to be forced against the relatively hard wedge-face portion of the pad and also to cause the overhanging portion of the covered breast of the heel and the shank portion of the shoe to be forced against the relatively soft wedge-face portion of the pad, and means for locking the shoe in clamped relation to the pad while the adhesive used to secure the flap to the shoe dries.
9. In a machine for applying by the use of an adhesive a covering flap to a Louis heel and the shank portion of a sole of a shoe, a support comprising stationary and movable members pivoted together, a wedge-shaped pad having one wedge-face portion which is made of relatively hard but slightly yieldable rubber and the other wedge-face portion of which is made of soft readily yieldable rubber, said pad being constructed and arranged to be interposed between the shank portion of the sole of the shoe and the breast of the heel against which the covering flap has been laid, clamps for forcing the upright portion of the covered breast of the heel against said one wedge-face portion of the heel, and means for swinging the movable member of the pad support to expand the pad thereby forcing said other wedge-face portion of the pad against the overhanging portion of the covered breast of the heel and the shank portion of the sole of the shoe.
10. A flap-applying machine having, in combination, a support for a shoe having a Louis heel and a sole from which a heel-breast covering flap has been split, a pad having a work-engaging portion which is made of relatively hard but slightly yieldable rubber and another work-engaging portion which is made of soft readily yieldable rubber, and means for effecting relative movement of the support and the pad to cause the relatively hard portion of the pad to apply a portion of the flap to the upright part of the breast of the heel and to cause the soft readily yieldable portion of the pad to apply another portion of the flap to the overhanging part of the breast of the heel and to the shank portion of the sole of the shoe.
11. In a machine for applying by the use of an adhesive a covering flap to a Louis heel and the shank portion of a sole of a shoe, a support comprising stationary and movable members, a wedge-shaped pad mounted upon the support and constructed and arranged to be interposed between the shank portion of the sole of the shoe and the breast of the heel against which the flap has been laid, said pad having a flat wedge-face portion made of relatively hard but slightly yieldable rubber, and a concave wedge-face portion made of soft readily yieldable rubber, clamps for forcing the upright portion of the breast of the Louis heel against said flat wedge-face portion of the pad, and means for operating the movable member of said pad support to force the concave wedge-face portion of the pad against the covered overhanging portion of the breast of the heel and against the shank portion of the sole of the shoe.
